UNITED STATES PATENT OFFICE

WILHELM HOSS, OF FRANKFORT, GERMANY, ASSIGNOR TO INTERNATIONAL PRECIPITATION COMPANY, OF LOS ANGELES, CALIFORNIA, A CORPORATION OF CALIFORNIA

APPARATUS FOR ELECTRICAL PRECIPITATION

Application filed May 9, 1928, Serial No. 276,431, and in Germany May 28, 1927.

This invention relates to apparatus for electrical precipitation of suspended particles from gases and particularly to electrical precipitation apparatus in which the gas to be treated is passed successively through a plurality of discharge electrode means and collecting electrode means, and in which the potential difference is graded in the respective precipitator units so as to successively subject the gases to electric fields of different intensities.

The principal object of the invention is to provide a novel arrangement for effecting the above described gradation of potential in the respective precipitator units.

According to this invention the gradation of potential is provided by mounting the electrode means (either the collecting or discharge electrodes or both) of the respective precipitator units or of certain of said units upon members composed of semi-conducting or resistance material, or by otherwise interposing layers of semi-conducting or resistance material in the electric circuit of the respective units, and making such semi-conducting member or layers for the respective units of different or graded resistances, as by difference in thickness thereof or difference in electrical conductivity.

The accompanying drawings illustrate embodiments of my invention and referring thereto.

Fig. 1 is a longitudinal section of the upper portions of the collecting and discharge electrodes of one form of the invention, together with the electrical connections therefor.

Fig. 2 is a horizontal section on line 2—2 in Fig. 1.

Fig. 3 is a vertical section of another modification of the invention.

Fig. 4 is a section on line 4—4 in Fig. 3.

Fig. 5 is a longitudinal section of the upper portion of an electrical precipitator showing the insertion of semi-conducting means in the high tension side of the respective precipitator units.

Fig. 6 is a section on line 6—6 in Fig. 5.

In Fig. 1 the discharge electrode means of three successive precipitator units are indicated at 1, 2 and 3 respectively, said discharge

electrode means each comprising one or more rows of fine wires, rods or the like mounted by any suitable supporting frame means indicated at 4 upon insulating supports 5. Each precipitator unit is also provided with collecting electrode means indicated at 6, 7 and 8 respectively, said collecting electrode means comprising, for example, plates disposed between the rows of discharge electrodes and consisting of conducting material such as metal, or of concrete or other semi-conducting material. The collecting electrodes may, however, be of any other suitable shape or construction.

In order to effect a gradation of potential in the successive precipitator units, the collecting electrode plates in the successive units may be mounted upon blocks or members of semi-conducting or resistance material, such as concrete, wood, or the like, of different thickness, so that a different thickness of semi-conducting material is interposed in the electric circuit of the respective units.

For example the collecting electrodes 6 of the first unit may be mounted upon semi-conducting or resistance members 10 which rest in turn upon supporting means 11 and the collecting electrodes 7 of the second unit may be mounted upon semi-conducting or resistance members 12, of less thickness than the members 10, resting upon supporting means 13, while the collecting electrodes 8 of the third unit may rest directly upon supporting means 15. The resistance means 10 and 12 may consist, for example, of blocks or strips of concrete or similar material which is of sufficient strength to support the weight of the electrodes and at the same time possesses the desired electrical resistance.

The discharge and collecting electrodes of the successive units are connected through the semi-conducting or resistance means aforesaid to any suitable common source of electric power. Said source of power may comprise a step-up transformer 25 whose primary winding is connected as by wires 26 to any suitable source of alternating current at ordinary commercial voltage and whose secondary winding may be connected by wires 27 to opposite contact members of

mechanical rectifier 28. One of the intermediate contact members of said rectifier may be grounded as at 29 and the supporting means 11, 13 and 15 for the several units 5 of the precipitator may also be grounded as indicated at 30. Wire 32 leads from the discharge electrodes or from any metallic supporting member connected thereto, such as a part of the supporting frame 4, to the 10 other intermediate contact of the rectifier.

It is evident from the above that the potential difference or electric field between discharge electrodes 1 and collecting electrodes 6 of the first unit will be reduced by 15 an amount equal to the potential drop in the semi-conducting supporting members 10 and the potential difference between discharge electrodes 2 and collecting electrodes 7 in the second unit will be reduced by an amount 20 equal to the potential drop in the semi-conducting supporting members 12, while the full potential delivered by the electrical equipment will be maintained between discharge electrodes 3 and collecting electrodes 25 8 in the third unit.

It will be understood that the discharge and collecting electrodes above described may be enclosed in any suitable housing means and the gas to be treated may be 30 passed in either direction through the successive electric fields. For example, the gas may pass from left to right in Fig. 1, in which case the gas is subjected to electric fields of successively increasing strength in 35 passing between the discharge and collecting electrodes of the successive units. In passing through these electric fields the suspended particles, such as dust, carried by the gas stream, become electrically charged and are 40 precipitated upon the collecting electrodes whence they fall to the bottom of the precipitator and may be removed in any suitable manner.

The gradation of potential effected in the 45 above manner may, for example, be such as to provide for a potential difference of 40,000 volts in the first unit, 45,000 in the second unit, and 50,000 volts in the third unit, in which case the resistance members 10 should 50 have a resistance sufficient to cause a potential drop of 10,000 volts across the same, while the resistance members 12 should have a resistance sufficient to cause a drop in potential of 5,000 volts.

55 The modification shown in Figs. 3 and 4 is similar in principle to that above described, the collecting electrode plates 17, 18 and 19 of successive units being shown, however, as mounted one above another instead of 60 alongside one another. Common discharge electrode means 20 are provided for all of said units, and the collecting electrodes for the successive units are mounted upon resistance members of varying thickness, which 65 rest in turn on suitable supporting ledges 21

on housing 22. Collecting electrodes 17, for example, may be mounted upon semi-conducting or resistance blocks 23 and collecting electrodes 18 upon resistance blocks 24 of less thickness than the members 23, while 70 collecting electrodes 19 may rest directly upon the housing. The housing may be grounded as indicated at 30 and the discharge electrode system may be connected by wire 32 to the high tension side of a source 75 of current which may, for example, be the same as shown in Fig. 1.

In Figs. 5 and 6 I have illustrated the insertion of layers of semi-conducting or resistance material between the high tension line and the discharge electrode systems of the several units of a precipitator. In this case the electrical precipitator is shown as comprising a casing 35 in which are mounted three successive groups of discharge and collecting electrodes. The collecting electrodes of the successive groups or units are indicated at 36, 37 and 38, said collecting electrodes being supported in any suitable manner as by means of supporting bars 39. The 80 discharge electrode systems of the successive groups or units are indicated at 40, 41 and 42 respectively, each of said discharge electrode systems comprising a plurality of rows of 85 discharge electrode members 43, such as fine wires or rods, hung between the respective collecting electrode. Said discharge electrode members may be hung from rods or pipes 44 which in turn are secured to transverse frame members 45. A yoke or other 90 suitable member 46 is secured to the frame member or members 45 for the discharge electrode systems of each group or section.

The supporting yoke 46 for one group of discharge electrode, such as group 42, rests 105 directly upon the common supporting member or bus bar 47, while the supporting yokes for the other groups of discharge electrodes rest upon semi-conducting or resistance members 48 and 49 respectively which have different values of resistance and which are in turn supported by supporting member 47. The supporting member 47 may be supported at its ends upon insulating supports 50 enclosed in suitable casing means 51. The electrical connections may, as shown, be substantially the same as in Fig. 1, the high tension wire 32 being in this case connected to the common supporting member 47, so that the 110 resistance of the semi-conducting members 48 and 49 is inserted in the high tension side, in series with the respective discharge electrode means 40 and 41. Resistance member 48 may have a greater resistance than member 49, for example, it may be twice as great. The collecting electrodes may be grounded 115 directly as indicated at 30.

The operation of either of the last two 120 modifications of the invention is substantially the same as in the form first described, the gas 125

being subjected in any case to electric fields of successively increasing (or decreasing) potential.

It will be understood that, in any of the forms above described, the gradation of potential may if desired be obtained by making the layers of resistance or semi-conducting material, in the circuits of the respective units, of materials having different conductivities instead of making them in different thickness, the result being the same in either case.

I claim:

1. An apparatus for electrical precipitation of suspended particles from gases comprising a plurality of electrical precipitator units arranged for passage of gas therethrough in series and each provided with collecting electrode means and discharge electrode means, a common supporting means for one of said electrode means for all of said units, members of semi-conducting material between said common supporting means and the respective electrode means supported thereby, said members constituting the sole electrical connection between said common supporting means and said electrode means and having different values of resistance in the respective units, and means electrically connecting said common supporting means and the other electrode means of the respective units to a source of electric power.

2. In apparatus for electrical precipitation of suspended particles from gases, a common supporting means, a plurality of groups of collecting electrode means supported thereby, and semi-conducting members of different values of resistance between said common supporting means and the respective groups of collecting electrodes.

3. In an electrical precipitating apparatus, a source of electric power, two electrical precipitating units each comprising discharge electrode means and collecting electrode means, a common supporting means for one of said electrode means for both of said units, means electrically connecting said common supporting means to said source of power, the electrode means of one of said units being mounted in direct electrical connection with said common supporting means, and semi-conducting means interposed between the electrode means of the other unit and said common supporting means and constituting the sole electrical connection there-between.

4. In an electrical precipitating apparatus, a source of electric power, two electrical precipitator units each comprising discharge electrode means and collecting electrode means, a common supporting means for one of said electrode means for both of said units, means electrically connecting said common supporting means to said source of power, and semi-conducting means having different values of resistance interposed between said

common supporting means and the respective electrode means supported thereby.

In testimony whereof I have hereunto subscribed my name this 30th day of April, 1928.

WILHELM HOSS.
